Primary Examiner — Robert M Spear*Assistant Examiner* — Darcey E Heflin(74) *Attorney, Agent, or Firm* — Vincent G. LoTempio; Kloss, Stenger & LoTempio; David T. Stephenson(57) **CLAIM**

The ornamental design for an apple holder, as shown and described.

DESCRIPTION

FIG. 1 is a back perspective view of an apple holder showing my new design;

FIG. 2 is a front perspective view thereof;

FIG. 3 is a right side view thereof with a left side view being a mirror image thereof;

FIG. 4 is a bottom elevational view thereof;

FIG. 5 is a top elevational view thereof; and,

FIG. 6 is an alternate perspective view showing the device in use.

The broken lines showing of an apple in FIG. 6 illustrates environmental subject matter and forms no part of the claimed design.
